Marie L. Gorham, Santa Barbara, Calif.

Application April 17, 1953, Serial No. 24,560

Term of patent 14 years

(Cl. D58—12)

To all whom it may concern:

Be it known that I, Marie L. Gorham, a citizen of the United States, residing in Santa Barbara, in the county of Santa Barbara and State of California, have invented a new, original, and ornamental Design for a Combination Dispenser and Disposal Box, of which the following is a specification, reference being had to the accompanying drawing forming a part thereof.

I claim:

The ornamental design for a combination dispenser and disposal box, substantially as shown.

MARIE L. GORHAM.
